CLAIM

The ornamental design for a cushion element for a sock, substantially as shown and described.

DESCRIPTION

FIG. 1 is a front perspective view of a cushion element for a sock showing our new design.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof.

FIG. 7 is a bottom plan view thereof; and,

FIG. 8 is a rear perspective view thereof.

The broken lines illustrate the environment of the claimed design and form no part of the claimed design. The contour lines shown in the drawings represent the three-dimensional character and contour of the article, and are not intended to illustrate material, surface ornamentation or surface decoration.
